UNITED STATES PATENT OFFICE.

HORACE LEE CLARK, OF RUTHERFORD, NEW JERSEY.

WICK-LIFT FOR LAMPS.

SPECIFICATION forming part of Letters Patent No. 481,748, dated August 30, 1892.

Application filed May 31, 1889. Serial No. 312,755. (No model.)

To all whom it may concern:

Be it known that I, HORACE LEE CLARK, a citizen of the United States of America, residing at Rutherford, county of Bergen, and State 5 of New Jersey, have invented and made certain new and useful Improvements in Wick Raisers or Lifts for Hydrocarbon-Lamps; and I do hereby declare that the following is a full, clear, and exact description and specification 10 of the same, reference being had to the accompanying drawings, making part thereof.

I have applied my invention to lamps having a central draft-tube and a circular hollow wick surrounding it and dipping into a 15 surrounding oil-chamber, and which is usually encompassed by a sleeve and is raised and lowered by a rod or stem, which moves vertically and is attached rigidly to said sleeve and extends upward through a slot in the 20 top of the oil-chamber. The distance to which the wick can be so raised is limited by the bulge on the lamp-chimney, because the top of the lifting stem or rod comes in contact with said bulb when the wick has been 25 raised sufficiently for said stem to strike. Thus a small portion only of the wick can be used. On account of the necessary nearness of the lifting-stem to the flame of the lamp as it rises the said stem heats, so that it is 30 liable to burn the hand of the operator.

The object of my invention is to obviate these difficulties; and to this end it consists in certain combinations of parts or elements fully set forth in and claimed at the end of 35 this specification.

In order that persons skilled in the art may understand, construct, and use my invention, I will proceed to describe it, referring to the drawings, in which—

40 Figure 1 is a view of my invention applied to a lamp shown in elevation, the lifting-stem being represented as at its full upward throw and standing at an angle to the perpendicular center line of the lamp and entirely clear 45 of the lamp-chimney bulb. Fig. 2 is a central vertical section of the same on line $x'y$ of Fig. 1, cutting the oil-chamber and wick device centrally, but showing the pivoted or flexible wick-lifting stem in elevation attached to the 50 lifting-sleeve. Fig. 3 is an elevation of the wick-lifting sleeve and its pivoted stem detached. Fig. 4 is a top view of the same. Fig.

5 is a top view of lifting-stem J and elongated tube U.

A is the lamp-stand, in which is held the oil-reservoir C, traversed vertically by a central draft-tube B, provided at its top above the reservoir C with a sliding perforated central air-distributing cap or cone F, fitted to slide on the tube B by an enlarged portion E of said 60 tube, cap, or cone, so that it can be raised or lowered at will, or removed, as the case may be. The wick N encompasses tube B. Its lower portion dips into the oil in chamber C and its top extends a little above the top of 65 said tube B when in condition to be lighted.

P is a tube which surrounds the draft-tube B a distance from it sufficient to permit the wick to pass up and down between them. The chamber formed between them is called 70 the "wick-chamber." This tube P is slotted vertically from its bottom up at O to permit the wick-lift flange H to slide up to its extreme throw without interfering with said tube P. The tube P extends upward to the height of 75 the top of tube B and extends downward a sufficient distance into the oil-chamber to perform its function of properly guiding the wick. It is secured a little below its top to a horizontal circular plate R', which plate R' 80 is provided with openings through it to permit the passage of air upward around the top of the wick. The plate R' is provided with vertical spring-clasps Q for inclosing and holding the chimney D, which rests upon 85 plate R in the usual manner. Another circular plate R' is attached to and surrounds tube P toward its bottom and is about the same size as plate R. The outer edges of these plates R and R' are connected by an upright 90 shell V, perforated with air-passages. Thus an air-chamber W is formed around the upper part of the wick and above the oil-chamber C, bounded by a portion of tube P, shell V, and top and bottom plates R and R'. 95 There is a circular opening in the upper surface of oil-chamber C and its inner edges are flanged upward, and the shell V of the above-mentioned air-chamber W rests within it and is supported by it on a bead, which is 100 formed on the shell V near its bottom. Thus the top of the oil-chamber is closed, except at one point, where it is provided with an oblong opening T through its upper surface, formed

by the flat tube U, through which the stem of the wick-lifter stem J passes. This wick-lift is composed of the short tube G, composed of a band of thin metal bent into circular form and riveted together at its ends by rivet L, which are flanged out or bent for the purpose. The lifting-stem J is formed of a flat strip of metal and pivoted at K to an upwardly-projecting extension of a laterally-projecting shank I, which is attached to the lifting-wick band G. (Shown in Figures 2, 3, and 4.) The position of this pivot K is not arbitrarily located; but I prefer to place it substantially as shown, depending upon the length of the upwardly-projecting extension of the shank. The wick-lift band G surrounds the wick N near its bottom and clasps said wick N upon tube B. It is provided with inwardly-projecting points M to cause it to hold firmly to the substance of the woven wick, so that as the lifting-stem J is raised and lowered it carries the wick N upward or downward on tube B, as may be desired, in lighting or extinguishing the flame on the top of the wick N. The lifting-stem J may be made of any convenient shape, either round or flat, and may be hinged to the upwardly-projecting extension of the shank of the wick-band in any convenient manner.

The essential feature of my invention consists in joining the lifting-stem J to an upwardly-projecting extension of the upwardly-projecting extension of the laterally-projecting shank I of the band G, flexibly or by a pivoted connection, in order that its upper end may be moved away from contact with the lamp-chimney and as far away as possible from the heat of the lamp-flame in lifting and lowering the wick N. To permit this to be done, the opening T in the top of the oil-chamber C, through which this lifter-stem J works, is necessarily elongated, as shown particularly at Fig. 5, to permit of horizontal motion to the stem J. In other devices for lifting the wick this has not been done, because in a vertically-moving lifter-stem side play is not required or desired.

In operating my invention the wick N is placed in the lifter-band G in about the position shown in Fig. 2. The air-chamber W having been removed from the top of the oil-chamber, the wick N and lifter-band G are slid down over the tube B. The tube P, flared out at its bottom, is then slid down over the wick N until the shell V takes into

and rests within the flanged top of oil-chamber C. The chimney D is then placed in its position. Oil is supplied to chamber C in the usual manner through an opening covered by a screw-cap, not in view in the drawings, but located in the top of the oil-chamber. The oil is sucked up by the wick N to its top and when lighted a brilliant flame is seen. The flame is supplied with air inwardly and upwardly through draft-tube B and perforations in cone F, outwardly through perforations in the shell V of air-chamber W, and upward through openings V' in plate R. As the wick burns away it is necessary to clean off the incrustation and raise the wick again to its former height above the tubes B and P. This is done by raising the lifting-stem J, seizing the handle S. It will be seen that the higher the wick N is raised by lifter-stem J and band G the farther it is possible to move the top of the lifter J away from a perpendicular line of action, and thus farther away from the chimney-bulb and the heat of the flame. This is accomplished by the pivoted joint K.

The position of parts shown in Fig. 2 represents the wick about two-thirds burned away. That in Fig. 1 as raised to its full height. When a new wick is first lighted, the handle S of the lifter-stem J is down near the top of the oblong tube U and the lifting-band G and bottom of wick N are near the bottom of tube B and oil-chamber C. The lifter-stem J will then be nearly vertical.

I do not claim, broadly, a pivotal draw-bar or lifting-stem, but only the particular construction shown herein, whereby the upper end of the bar is caused to fall away from the burner more rapidly than when its lower end is pivoted directly to a simple shank projecting laterally from the wick-band.

Having now fully described my invention and the manner in which I have embodied it, what I claim as new, and desire to secure by Letters Patent, is—

In a wick-adjusting device for central-draft lamps, the combination, with a wick-band having a laterally-projecting shank constructed with an upwardly-projecting extension, of a draw-bar having its lower end pivotally connected with the upper end of the said extension of the shank, substantially as set forth.

HORACE LEE CLARK.
